UNITED STATES PATENT OFFICE.

JOHN B. COLLIN, OF ALTOONA, PENNSYLVANIA.

IMPROVEMENT IN EXHAUST-PIPES FOR STEAM-HAMMERS.

Specification forming part of Letters Patent No. 178,271, dated June 6, 1876; application filed April 25, 1874.

To all whom it may concern:

Be it known that I, JOHN B. COLLIN, of Altoona, in the county of Blair and State of Pennsylvania, have invented certain new and useful Improvements in Steam-Hammers, of which improvements the following is a specification:

As heretofore constructed and operated, the steam-hammer has been provided with an exhaust-pipe, into which the steam from the cylinder escaped, and by which it was conducted off into the atmosphere above the roof of the building in which the hammer was worked. Such buildings are generally provided with high roofs, to improve the ventilation, and the exhaust-pipe is consequently very long, sometimes forty feet in length. This long pipe was also of small diameter, and was simply attached to the side of the hammer-frame, so as to cover the exhaust-opening from the steam-cylinder, being curved or provided with an elbow to bring it into an upright position.

With such a length of small pipe thus supported, the vibrations of the hammer-frame, with every blow of the hammer, make the pipe rock and tremble, and this rocking and trembling soon causes the pipe to leak, and this permits the escape of steam and hot water, which issue through the leaks, and scald the workmen, besides subjecting them to other inconveniences in managing the hammer and the metal being worked.

The intermissions of the exhaust establish an alternation of puffs of steam up the pipe, and rushes of air down the pipe, with a constant resistance of the one current against the other, producing throughout the exhaust-pipe a seesaw of steam and air, which occasions a considerable loss of power. Again, by reason of the great height or length of the exhaust-pipe there is so constant a "back pressure" upon the hammer-piston as to sensibly impair the force and efficiency of the blow given by the hammer, and this long small pipe being continuous, the steam condenses therein more rapidly than is desirable, so that less of it is discharged into the atmosphere than should be, and the condensed steam constantly running down the continuous pipe accumulates at its lower end, and runs back into the

cylinder through the exhaust-opening, so as to very rapidly destroy the packing of the piston-rod, and not only requiring the frequent renewal of the packing, but meanwhile occasioning leakages, which interfere with the hammer-man, and produce imperfections in the welding of the metal.

It is the object of my invention to obviate these difficulties by preventing any such rocking and trembling of the exhaust-pipe as will cause leakage therein, by establishing a continuous current, of steam and air combined, upward, from the exhaust to the atmosphere, in place of the intermittent alternations or seesaw up and down of puffs of steam and rushes of air, as above mentioned, thus saving the power heretofore lost, by relieving the hammer-piston from back pressure, thus delivering the blow of the hammer more efficiently, and by carrying off the condensed steam, so that it shall not accumulate in the exhaust-pipe and run back into the cylinder, thus preventing the wear of the packing of the piston-rod, and relieving the workman and the work from the leakages from that source.

To these ends my invention consists, as illustrated in the accompanying drawings, which form part of this specification, and in which Figure 1 is a vertical section, and Fig. 2 a plan, in combining with the exhaust-opening of the steam-cylinder a short pipe, A, the lower end of which has a flange, E, by means of which this pipe is secured to the hammer-frame around the exhaust-opening. The other end of this pipe A opens into the lower end of a pipe, D, which is supported independently of the hammer-frame, and which extends up through the roof, but is not in any way attached to the pipe A. The pipe D should have a diameter four or five times that of the pipe A, so that there will be an annular opening at the lower end of the pipe D, around the free end of the pipe A, in which annular space the free end of the pipe A may vibrate or rock, and through which there may be a free access of air from the bottom to the top of pipe D.

It should be understood explicitly that although the drawing shows the pipe D supported upon the base of the block which supports the pipe A, this is only for convenience.

of representation, and that in practice the supports for the pipe D have, as above stated, no connection with the hammer-frame.

Below the free end of the pipe A, and under the lower end of the pipe D, I arrange a receiver, B, and conduit C for the condensed steam, which falls or trickles down the pipe D into the receiver, and is carried off by the conduit C to any point suitable for its discharge.

The connection or attachment of the pipe A to the hammer-frame should be made practically steam-tight, in any of the usual ways.

With this construction, it will be seen that only the small short pipe A is subjected to the jars of the hammer-frame, and its vibration is thus so modified that the connection of the pipe with the frame is not likely to be strained or to leak. The disconnection of the exhaust pipe A from the pipe or chimney D relieves the piston entirely from back pressure, and the chimney D, being supported independently of the hammer-frame, is not affected by the jarring of the hammer, as heretofore. Moreover, the open lower end of the pipe or chimney D insures a constant current or draft of

air through the chimney, accelerated by the escape of steam from the exhaust-pipe into the chimney, and continuously ascending, instead of two currents seesawing, as above described, and by conducting the condensed steam down the pipe D and intercepting it, so that it does not run back into the exhaust-pipe and into the cylinder, I prevent the wearing of the packing and the attendant leakage from this source.

Having thus described the nature and objects of my invention, what I claim as new, and desire to secure by Letters Patent, is—

1. The combination, with the exhaust of a steam-hammer, of a short exhaust-pipe and an independent chimney, the combination being and operating substantially as and for the purposes described.

2. The combination of the exhaust-opening, the exhaust-pipe, the independent chimney, and the receiver, substantially as and for the purposes described.

J. B. COLLIN.
